UNITED STATES PATENT OFFICE.

LEE J. GARY, OF CHICAGO, ILLINOIS, ASSIGNOR TO UNIVERSAL OIL PRODUCTS COMPANY, OF CHICAGO, ILLINOIS, A CORPORATION OF SOUTH DAKOTA.

PROCESS AND APPARATUS FOR CRACKING PETROLEUM.

Application filed March 14, 1921, Serial No. 452,214. Renewed February 20, 1928.

This invention relates to improvements in a process and apparatus for cracking petroleum oils and refers more particularly to a process in which the oil is heated in a continuous coil and then delivered to expansion chambers where vaporization takes place, the carbon is precipitated and the vapors drawn off and condensed and collected.

The present invention refers more particularly to the manner of maintaining a balanced pressure in a battery of stills or battery of expansion chambers. In the present invention, balancing pressure may be obtained either from a gas header leading from the expansion chambers or from a gas header leading from the dephlegmators or reflux condensers. This will permit of maintaining the water condensers and receivers under a reduced pressure from the rest of the system or even at atmospheric pressure or under a vacuum. The present invention also permits of a balanced pressure being maintained on the expansion chambers and a separate balanced pressure maintained on the reflux condensers if desirable. In the cracking of petroleum oil, it is very desirable to maintain close adjustments of pressure on various parts of the system, which is accomplished by the present invention in a simple manner.

In the drawings:

Fig. 1 is a top plan view of my improved apparatus.

Fig. 2 is a view, partly in side elevation and partly in vertical section, of the same.

Referring in detail to the drawings, 1, 2 and 3 designate the furnaces in which are mounted the heating coils 4 which may take the form of continuous lengths of 4" pipe. Each coil 4 is connected to a feed pump 5 leading to any suitable source of raw oil supply. The discharge side of each coil is connected by transfer line 6 in which is interposed a throttle valve 7 to a transfer header 8. Each transfer header 8 is connected by branches 9 to the vertical expansion chambers 10 located outside of the fire zone. It will be noted that there are two of these expansion chambers 10 for each heating coil whereby one may be cut out of the system and cleaned while the other is in use or both may be simultaneously used. Each expansion chamber 10 is provided with a residue drawoff pipe 11, controlled by throttle valve 12 and with vapor outlet pipe 13 controlled by throttle valve 14, which pipe 13 extends into the lower side of a vertical dephlegmator 15. From the lower part of each dephlegmator 15 extends a reflux pipe 16 controlled by throttle valve 17, leading back to the corresponding feed pump 5. The top of each dephlegmator is provided with a vapor outlet pipe 18 controlled by throttle valve 19 and leading to the top of condenser coil 20 seated in condenser box 21. The lower end of each coil 20 is connected by pipe 22 having throttle valve 23 to the top of receiver 24. Each receiver 24 is provided with pressure gauge 25, liquid level gauge 26, liquid drawoff pipe 27, controlled by throttle valve 28 and gas outlet pipe 29 controlled by throttle valve 30. Each receiver is also provided with a pipe 31 having throttle valve 32 and leading to a vacuum pump 33. Where the vacuum pumps are used, the receivers may be provided with vacuum gauges 34.

Referring now more particularly to the novel features of the invention, from each expansion chamber 10 extends a short riser pipe 35 controlled by throttle valve 36 and leading to a gas header 37, which gas header 37 is controlled by a master control throttle valve 38. The condensable vapors which pass up into this header will be condensed and fall back into the expansion chamber so that in effect the headers will primarily contain incondensable gas. If desired, the header may be provided with a liquid trap (not shown) whereby condensate may be drawn off from time to time either for test purposes or to remove the condensate from the header. Inasmuch as all of the expansion chambers are connected to this header, it will be seen that a uniform pressure may be automatically maintained on all of the expansion chambers and heating elements. In such case, the dephlegmators and the rest of the system may be maintained under a lower pressure. For example, a pressure of 300 pounds may be maintained on the heating coil and the expansion chambers, by suitably regulating the valves 12 and 14 while a pressure of say, 100 pounds may be maintained on the dephlegmators, condenser coils and receivers. Or as another way of operating the process, a pressure of 300 pounds may be maintained on the heating tubes and expansion chambers and a vacuum of from 15" to 20" maintained on the dephlegmator, condenser coil and receivers.

I have above described the use of a header connected to the expansion chambers. In addition, I provide a second header 39 controlled by a master throttle valve 40 and 5 connected by the branch pipes 41 having throttle valves 42 to the dephlegmators. This header may operate in exactly the same way as the header previously described to maintain a balanced pressure on the dephleg- 10 mators, expansion chambers and heating coils. In such case, the valves 7 and 14 will be opened and the pressure regulated by the various valves 19. In this case, a 200 to 300 pounds pressure may be maintained from 15 the heating coils through the dephlegmators and a reduced pressure, or even atmospheric, or even a vacuum, maintained on the various condenser coils and receivers. In such case, the header 37 may be cut out of the system 20 by closing the various valves 36 in the branch pipes 35.

It has been obvious to those versed in the art of cracking hydrocarbon oils that the use of differential pressures as explained 25 will result in an increased yield of light hydrocarbons from certain types of charging stock. In fact, due to the frictional resistance encountered in the flow of oil from the heating coils to the receiver, there is always 30 a slight reduction in pressure, that is, there is a slightly higher pressure maintained on the heating coils than on the condenser and receiver, in order to force the oil and vapors through the system. By regulating this reduction in pressure, and maintaining a pre- 35 determined relatively high pressure on the dephlegmator and throttling the pressure on the flow to the condenser, it is possible to accurately reduce it and operate under a 40 relatively low pressure. Numerous experiments have proven the advantage of this reduction in pressure and condensing under a lower pressure than the pressure on the dephlegmator in certain types of oils. 45 As still another method of operating the process, both of the headers may be used, in which case a pressure of 250 pounds may be maintained on the expansion chambers and heating coils and the balancing effect 50 produced on these elements from the header 37. A reduced pressure of say, 150 pounds

may be maintained on the various dephleg- 55 mators by suitably throttling the valves 14 and 19 and opening the various valves 42. In this case, the reduced pressure or vacuum may be maintained on the condenser coils and receivers.

It is to be understood that I have here referred more particularly to the valves which control the headers. It is to be understood that the other valves shown may be suitably operated to regulate the pressure and also, for example, to cut any part of the apparatus out of the system.

I claim as my invention:

1. An apparatus for cracking hydrocarbon oil, comprising a plurality of independent heating coils, a plurality of expansion chambers, into which heated oil from said coils is discharged, a dephlegmator associated with each of said enlarged expansion chambers, pressure reducing means interposed between each enlarged expansion chamber and its associate dephlegmator, a common header in communication with the vapor space of each of said expansion chambers, a second header in communication with each of said dephlegmators, whereby a uniform pressure can be maintained in said dephlegmators, lower than a uniform super- 70 atmospheric pressure maintained in said enlarged expansion chambers, and means connected to said dephlegmators for condensing and collecting vapors issuing therefrom.

2. A continuous process for cracking oil, 75 consisting in simultaneously passing a plurality of streams of oil through independent heating zones, wherein the streams of oil are raised to cracking temperatures, in delivering the heated oil from said streams into a 80 plurality of expansion chambers, in passing the vapors from said expansion chambers through a plurality of dephlegmators, in maintaining a uniform pressure in all of said dephlegmators and in maintaining in 85 said expansion chambers a uniform super- atmospheric pressure higher than the uniform pressure maintained in said dephleg- 90 mators, and in taking off uncondensed vapors from said dephlegmators for condensation and collection.

LEE J. GARY.
